(57) **CLAIM**

We claim the ornamental design for a tabletop remote load control device, as shown and described.

DESCRIPTION

This is a continuation application of U.S. Design patent application Ser. No. 29/575,106, filed Aug. 22, 2016.

FIG. 1 is a perspective view of a tabletop remote load control device.

FIG. 2 is a top view thereof.

FIG. 3 is a left side view thereof.

FIG. 4 is a right side view thereof.

FIG. 5 is a front view thereof; and,

FIG. 6 is a rear view thereof.

The bottom view forms no part of the design and is omitted. The broken lines showing portions of the tabletop remote load control device are for the purpose of illustrating environmental structure and form no part of the claimed design.
